UNITED STATES PATENT OFFICE

ERICH R. ZADEMACH, OF ELIZABETH, NEW JERSEY, ASSIGNOR TO METALWASH MACHINERY COMPANY, OF NEW YORK, N. Y., A COPARTNERSHIP COMPRISED OF HERMAN O. BOEHME, ERICH R. ZADEMACH, AND ALBERT C. NOLTE

METAL-WARE CLEANING

Application filed October 1, 1927. Serial No. 223,465.

This invention relates to the art of automatically cleaning metalware of the oil, grease and dirt which has accumulated thereon during the process of its manufacture.

5 The principal object of the invention is to provide simple and inexpensive means whereby flat or shallow work material, such as automobile license plates, pie-tins, etc., may be easily and quickly placed in position 10 relative to a conveyor belt which automatically carries it through washing and drying chambers.

Another object is to provide such means which will maintain work material of the 15 character described firmly in position during its passage through such chambers.

A further object is to provide such means which will automatically release the work 20 material from its supporting means upon the completion of the cleaning and drying operations.

A still further object is to provide such means which may be readily installed on or used in conjunction with conveyor belts of 25 existing types.

The following is a description of work-holding means embodying the invention in the forms at present preferred; but it will be understood that various modifications 30 and changes may be made without departing from the spirit of the invention and without exceeding the scope of the claims.

The invention will best be understood by reference to the accompanying drawings, 35 wherein it is illustrated in its preferred forms, and in which Fig. 1 is a vertical cross-section of a portion of a washing or drying machine embodying one form of the invention; Fig. 2 is a fragmentary detail, on a 40 larger scale, showing a cross-section of a wire-mesh conveyor belt of a well-known type, associated with which belt is a work-holder embodying the present invention, together with work material in operative position 45 therein; Fig. 3 is a fragmentary detail showing a side elevation of the parts illustrated in Fig. 2; Fig. 4 is a fragmentary detail showing a cross-section of a wire-mesh conveyor belt, such as is illustrated in Fig. 50 2, but with a modified form of means for at-

taching the work-holder to the belt; Fig. 5 is a plan of a work-supporting frame and associated parts embodying a modified form of the invention which is adapted to be used in conjunction with any conventional type of conveyor belt; Fig. 6 is a cross-section on the line 6—6 of Fig. 5, illustrating certain desirable structural features pertaining to this form of the invention; and Fig. 7 is a fragmentary sectional detail on the line 7—7 of Fig. 6, illustrating a method of attaching the springs which comprise one portion of the invention to their supporting means.

Like reference characters indicate like parts throughout the drawings.

Referring to the drawings (Fig. 1), 1 is a portion of the housing of a metalware washing and drying machine, which may be of conventional form and design, and which is here shown and described merely for the purpose of making clear the mode of operation of the present invention. The machine as here illustrated is equipped with a wire-mesh conveyor belt 2, adapted to continuously carry to the left-hand, or discharge, end, 75 work material which has been placed in the right-hand end (not shown) of said machine. The upper side of the conveyor belt may be supported upon rotatable shafts, such as 3; and the lower side thereof may be supported at its edges by rotatable wheels or sprockets, either idle or driven, such as 4 and 5. The belt may be driven, through a wheel or sprocket such as 6, or through rollers, by a motor and suitable transmission means (not shown). The machine is provided with well-known devices, indicated as 7 and 8, for projecting suitable washing liquids under pressure upon the work material during its 80 passage through the washing chamber.

90 Coils or helices, 9—9a, formed of wire, are, in the particular form of the invention illustrated in Figs. 2 and 3, threaded through the interlocking loops of a wire-mesh conveyor belt 11, in a manner to anchor such helices to said belt and in longitudinal relation thereto. The work material (here illustrated as a thin flat sheet such as is employed in the making of automobile license plates) is readily placed in position between two coils 95 100

in each of two adjacent helices. The spring tension of these coils is sufficient to firmly hold such material in position during its progress through the washing and drying chambers.

A modified form of means for attaching the helices to the loops of the wire-mesh belt is shown in Fig. 4, wherein, instead of threading such helices through the interlocking belt loops, as indicated in Fig. 3, they are connected to said belt by means of small rings, such as 12-12a. With either method of attaching the helices to the conveyor belt, the invention possesses the novel feature that, as the belt passes around the wheel or sprocket 6 at the left-hand or discharge end of the machine (Fig. 1), the coils of the work holders open, thus permitting the work material to fall therefrom by the action of gravity.

20 In Fig. 5 is shown a plan view of a modified form of the invention, adapted to be used in conjunction with any type of roller or belt conveyor. A frame 13, preferably formed of wood, is provided with a plurality of longitudinal members, 14, which may also be made of wood, and to which the work-supporting helices 15 are adapted to be attached. The tops of these longitudinal members are preferably tapered in order that the washing liquid may readily drain therefrom. Each of the longitudinal members is provided with a plurality of perforated metal anchoring blocks, 16, through which the helices are threaded in the manner indicated in Fig. 7. 30 By thus anchoring each helix at intervals throughout its length, it is not only firmly supported to receive the work material (here illustrated as a pie-tin, 17), but the advantage is also obtained of uniform expansion of the coils, by reason of confining such expansion within the sections between adjacent anchoring blocks. But for such an arrangement, the insertion of a considerable number of pieces of work material would result in the 40 opening of the coils in one portion of the helix at the expense of a corresponding compression of the coils in another portion thereof—thereby reducing the capacity of the work-holder and also rendering more difficult the insertion in and removal therefrom of such work material. This feature of the invention is particularly desirable where the work material is not flat but where, as in the case of the flanged pie-tin 17, it is of such 50 form as to necessarily cause considerable expansion of the coils of the helical work-holder.

The invention comprises novel, inexpensive and highly efficient means for readily receiving and maintaining in position certain classes of work material, in order that it may be subjected to the washing and drying operations. In the form illustrated in Figs. 1, 2, 3 and 4, adapted for use in conjunction with wire-mesh belts, the invention embodies the

additional and desirable feature of automatically ejecting the work material from its holders upon completion of the washing and drying process. In the form illustrated in Figs. 5, 6 and 7, it embodies simple and practical means for positioning and holding articles of divers shapes and sizes, whereby such articles may be carried through washing and drying machinery equipped with any type of conveyor belt.

I have described what I believe to be the best embodiments of my invention. I do not wish, however, to be confined to the embodiments shown, but what I desire to cover by Letters Patent is set forth in the appended claims.

I claim:

1. A metalware cleaning machine including a wire-mesh conveyor belt and a work-holder comprising a plurality of wire helices attached to said belt and in longitudinal relation thereto.

2. In metalware cleaning mechanism, the combination of a belt for conveying articles and a work-holder comprising a coil of wire attached to said belt longitudinally thereof.

3. In metalware cleaning mechanism, the combination of a work-holder comprising a longitudinally movable coiled wire and means for carrying said holder through said chamber and flexing it at a predetermined point to release the work pieces.

4. In combination, a conveyor comprising an endless, flexible belt, and end rollers supporting the same, means for driving the conveyor, and a resilient coiled work-holder carried by the belt and extending longitudinally thereof and arranged to have its coils spread when passing around the end rollers.

In testimony whereof I have affixed my signature to this specification.

ERICH R. ZADEMACH.
